(57) CLAIM

The ornamental design for a men's watch box, as shown and described.

DESCRIPTION

FIG. 1 is a perspective view of a men's watch box showing my new design;

FIG. 2 is another perspective view of the men's watch box with shown in an alternate open configuration;

FIG. 3 is a front elevational view of the men's watch box of FIG. 1;

FIG. 4 is a rear elevational view of the men's watch box of FIG. 1;

FIG. 5 is a left view of the men's watch box of FIG. 1;

FIG. 6 is a right view of the men's watch box of FIG. 1;

FIG. 7 is a top plan view of the men's watch box of FIG. 1; and,

FIG. 8 is a bottom plan view of the men's watch box of FIG. 1.

The broken lines illustrate portions of the men's watch box that form no part of the claimed design.

1 Claim, 8 Drawing Sheets
